CLAIM

The ornamental design for a carton, as shown and described.

DESCRIPTION

FIG. 1 is a perspective view of the carton showing my new design;

FIG. 2 is a plan view of the blank from which the carton is erected. The thickness of the blank is that of conventional paperboard;

FIG. 3 is a top view of the carton;

FIG. 4 is a front elevational view of the carton, the rear view being identical;

FIG. 5 is a bottom view of the carton; and,

FIG. 6 is an end view the carton, the opposite end being identical.
